UNITED STATES PATENT OFFICE

JOSEPH OTTI, OF OKLAHOMA CITY, OKLAHOMA

RIM TOOL

Application filed March 9, 1926. Serial No. 93,438.

This invention relates to a device for removing rims from tires, by distorting the rim until circularity has been temporarily destroyed, thus decreasing the diameter or 5 circumference of the rim relatively to the circularity of the inside of the tire, when the rim may be easily removed.

In like manner, it is also an object of the invention to restore the said circularity of 10 the rim, after the same has been inserted within the inner edge of the tire, and to snap it back in place, by allowing the proper abutment of the rim ends, when the locking devices may register.

It is another object of the invention to 15 provide a collapsible tool, operable essentially upon itself and to cause that tool to grip and hold the rim in a collapsed position for allowing easy removal of the casing, and 20 for replacing the rim.

It is also an object of the invention to provide means for holding the ends of the rim in proper abutment, while the rim is being locked.

On the sheet of drawings, accompanying 25 and forming a part of the specification,

Figure 1 is an elevation view of the rim, and the tool applied, ready for the breaking operation;

Figure 2 is a view showing the tool locked or hooked to the rim as broken to hold the rim in contracted or collapsed position;

Figure 3 shows a fragmentary view of a 30 rim and the tool in another initial position 35 for breaking, and separating the rim;

Figure 4 shows the tool and rim, as above, but separated or broken;

Figure 5 is a fragment of a rim and showing a means for gripping the rim, to 40 operate with the tool to remove those rims where no lugs or bolt eyes are formed thereon;

Figure 6 is a cross-section of a rim, and showing a rim gripping device in section;

Figure 7 is a fragmented detail view in 45 connection with the method of applying the tool to the rim gripping clamp, and

Figure 8 is still another modified view of 50 a rim gripping means for another form of rim.

In these views, similar characters of reference will indicate similar parts.

The rim shown is designated by 10, and is provided with the usual bolt lugs 11, having bolt holes 11'. In other instances the 55 lugs are omitted, and holes are formed in the rim as shown at 27.

The tool is constituted of a lever 13 terminating in an end 22, laterally extending from the lever 13, adapted to hook into hole 60 11' of one of the lugs 11 by means of the lug 14. This lever end 22 may be provided with a slot 15, and a pin 16 travels in said slot 15 and is carried by an arm or secondary lever 17 having a stud 18 to enter into the 65 hole 11' of the lug 11. This lever 17 is provided with an offset in the form of a head 19, and is provided with a heel 20 to bear upon the inner part of the rim near the breaking intersection. Where a rim is not 70 provided with lugs, the studs 14 and 18 may still be hooked into the holes 27 in the rim or the same tool may be used in connection with grips to engage the rim 10, more particularly shown in detail in Figures 5, 6 and 75 7, and to be more fully hereinafter set forth. This allows the tool to be used in connection with lugless rims, and in connection with holes formed in the rim, such as 27, and in connection with grips for gripping the rim. 80

By reference to Figures 3 and 4, respectively, it will be seen that the tool may be reversed, the stud 18 engaging a lug and the long end 23 of the lever 13 engaging the 85 rim; and in case of a lugless rim the same method of operation may be employed by hooking 18 over the edge of a rim.

Some rims are lugless and in case of these, such as 12, (see Figures 5, 6 and 7) a steel 90 clip, is bent upon itself to form legs 24 and 25, the former having a gripping beak 26 for taking over the edge of the rim 12 while the leg 25 takes against the face of the rim, as seen in Figure 6. These clips are provided, 95 of course, in the plural, as may be needed. The head 19 of the tool will be associated therewith by having the end holding the stud 18 inserted between the walls 24 and 25 of the grip, and secured thereto while a like 100

connection with another grip may be had with the end 14 of the lever 13.

By reference to Figure 8 the studs 14 and 18 of the head 19 and the lever 13 may be attached to unions on the end of a lever 28 and having a neck 29 passable through holes 30 in the rim, and this neck 29 is provided with a head 31 to retain the stud in position. With this sort of a hitch, the tool may operate in the usual manner.

Again, in the case of lugless rims, the lever 13 may be sufficiently pulled over until the pin 21 passes the outer edge of the rim 10 when it can drop back and hook onto the outer edge of the rim.

The operation is as follows:

Figure 1 shows the initial or first position of the tool, studs 14 and 18 being hooked into the holes of the lugs 11 as indicated. Pulling the lever 13 in the direction opposite to that shown, or to the position shown in Figure 2, will both cause the pin 16 to move in the elongated slot 15 and re-position the lever 13 and the secondary lever 17 to force the heel 20 against the rim and at the same time pull the opposite end of the rim away from the one being pressed down by the heel 20 and thus allow the two ends to pass each other (see Figure 2). This also contracts the rim and allows it to be withdrawn readily from the casing.

By the reverse operation, the rim may be restored to its original position or shape in the casing for holding the same, and the free ends of it properly snapped into place for locking co-operation.

Attention is now called to the fact that this tool may be used to have its pins 14, 18 and 21 hook into the holes in the lugs 11, or some of them in the holes while others hook over the outside of the rim, or in the position of Figure 2 the pin 21 may be pressed against the inside of the rim instead of the heel 23 and again, this same pin may act as a hook to the outside of the rim while pin 18 is in the lug, as can be seen by Figure 2 if it is desired to break the rim in the opposite direction to that shown. Again, should it be desirable, the pin 21 in Figure 2, may be hooked over the outside of the rim instead of in the lug hole as shown. It is also practical in the case of a lugless rim to press pin 18 to the inside of rim, and pin 21 to the outside of the rim, and make the break or to press pin 21 to the inside of the rim and pin 18 to the outside of the rim and produce the same result.

Having thus described this invention, I claim:

1. A rim tool comprising two levers each having means at one end for detachably connecting it to the rim, one lever being provided with an opening, a pivot carried by the other lever and having a relative movement in said opening in said first named lever said move-

ment causing the end of one lever to move toward the rim and force one end thereof out of line with the other while the continued movement of the lever collapses the rim, causing one end to lap the other.

2. A rim tool comprising two levers each having means at one end for detachably connecting it to the rim, one of the levers having a curved slot therein and the other end of the other lever having a pivotal connection with said slot, such other lever being so shaped that as the movement of the slotted lever causes the end of the other lever to move along the slot said other lever moves toward the rim and forces one end thereof out of line with the other while the continued movement of the lever collapses the rim, causing one end to lap the other.

3. A rim tool as specified in claim 2 in which said slotted lever during its further movement maintains the other lever in a position to hold the rim ends slightly spaced.

Signed at Oklahoma City, in the county of Oklahoma and in the State of Oklahoma, this 6th day of March, in the year of our Lord, nineteen hundred and twenty-six.

JOSEPH OTTI.
